United States Patent

Des. 239,697
Patented Apr. 27, 1976

239,697

BOTTLE

Kenneth W. Hunt, Hialeah, Fla., assignor to Hunt-Wilde Corporation

Filed Nov. 27, 1974, Ser. No. 527,622

Term of patent 14 years

Int. Cl. D9—01

U.S. Cl. D9—37

FIG-1

FIG-2

FIG-3

FIG-4

FIG-5

FIG. 1 is a side elevational view of a bottle showing my new design, the opposite side being a mirror image thereof;

FIG. 2 is an elevational view looking from the right of FIG. 1;

FIG. 3 is a top plan view of FIG. 1;

FIG. 4 is an elevational view looking from the left of FIG. 1; and

FIG. 5 is a bottom plan view of FIG. 1.

I claim:

The ornamental design for a bottle, as shown and described.
